UNITED STATES PATENT OFFICE.

CHARLES J. STUART, OF PUYALLUP, WASHINGTON.

REFRIGERATOR-BOX.

SPECIFICATION forming part of Letters Patent No. 643,013, dated February 6, 1900.

Application filed August 29, 1899. Serial No. 728,883. (No model.)

To all whom it may concern:

Be it known that I, CHARLES J. STUART, a citizen of the United States, residing at Puyallup, in the county of Pierce and State of Washington, have invented certain new and useful Improvements in Refrigerator-Boxes; and I do declare the following to be a full, clear, and exact description of the invention, such as will enable others skilled in the art to which it appertains to make and use the same.

The invention relates to refrigerator-boxes for the transportation for long distances of perishable goods—such, for instance, as berries and other fruits.

15 The object of the invention is to so construct a refrigerator-box that the ice may be easily and expeditiously replenished as necessity may require it while in transit without handling the box or disturbing the fruit when 20 the boxes are placed one upon the other.

To this end the invention consists in certain features of construction and combination of parts, which will be hereinafter fully described and claimed.

25 In the drawings, Figure 1 is a perspective view with the lid of the box swung open and the hinged front section swung down. Fig. 2 is a vertical sectional view. Fig. 3 is a view of one of the side pieces of the box, showing 30 its slatted construction.

In the accompanying drawings the same reference characters indicate the same parts of the invention.

1 denotes the box, which may be of any desired shape, and 2 denotes its cover, which is preferably hinged thereto. The sides, bottom, and cover of the box are each preferably composed of two pieces *a b*, with an interposed lining or sheet of asbestos *c*. The 35 inner sides of the box are provided with vertical slats 3 to form air-channels. The front of the box, near its top, has a hinged section 4, which when folded up is flush with the upper edge of the box and is adapted to be secured 40 to the cover by a fastening 5.

45 6 denotes an ice pan or receptacle which is fitted in the top of the box and supported upon ledges 7.

8 denotes a short drip-tube, which is secured 50 to the bottom of the pan 6 and leads into the funnel end of a drip-tube 9, secured to one of the sides of the box and leading out of the

bottom thereof. It will thus be seen that when the pan is inserted in position its short drip-tube, which is preferably flexible, will fall 55 into and communicate with the drip-tube of the box and conduct the water in the pan out through the bottom of the box.

In shipping goods the boxes are usually placed one on top of the other, and heretofore 60 great difficulty has been experienced in replenishing the boxes with ice, as it became necessary to remove the boxes one from over the other in order to raise the lids to supply 65 the interior with ice.

My invention provides for the refilling of the ice-pans without disturbing or handling the boxes, as all that is necessary is to unfasten the hinged section 4 from the cover, swing it down, remove the pan, fill it with 70 ice, and then put it back in place in the box, after which the hinged section is raised and secured in position.

It will be noticed that the hinged section, like the sides of the box, is provided with slats 75 10 to form ducts that communicate with the air-ducts in the front side of the box, so as to furnish the goods within the box with a free circulation of cold air.

It will of course be understood that various 80 changes in the form, proportion, and the minor details of construction may be resorted to without departing from the principle or sacrificing any of the advantages of this invention.

Having thus described the invention, what is claimed, and desired to be secured by Letters Patent, is—

A box of the character described composed of the end pieces, the side pieces and the base, 90 fixed together, and provided with a cover, one of the side pieces being of less height than the other side piece and the end pieces, a strip having its lower edge hinged to the upper edge of the shorter side piece, and when folded up 95 in place has its upper edge flush with the upper edges of the ends and the other side piece, the interior walls of the box being provided with vertical cleats to form air-ducts, and the interior wall of the hinged strip being provided with cleats to form air-ducts and continuations of the cleats on the shorter side of the box, an ice pan or receptacle arranged 100 and supported immediately beneath the cover

of the box and capable of being withdrawn through the opening in the front of the box formed by swinging the hinged strip downwardly, and a drain-pipe for said pan or receptacle, substantially as and for the purpose set forth.

5 In testimony whereof I have hereunto set

my hand in presence of two subscribing witnesses.

CHARLES J. STUART.
